UNITED STATES PATENT OFFICE.

ROBERT J. WISNOM, OF VIRGINIA CITY, NEVADA

ANODE.

No. 903,939.

Specification of Letters Patent.

Patented Nov. 17, 1908.

Application filed May 7, 1907. Serial No. 372,448.

To all whom it may concern:

Be it known that I, ROBERT J. WISNOM, a subject of the King of Great Britain, residing at Virginia City, in the county of Storey, 5 State of Nevada, have invented a certain new and useful Anode; and I do hereby declare the following to be a full, clear, and exact description of the invention, such as will enable others skilled in the art to which 10 it appertains to make and use the same.

This invention relates to anodes, and more particularly to the anodes used in the precipitation of precious metals from cyanide or like solutions.

15 It is desired to provide an anode that will have a longer period of usefulness than those at present in use.

It is also desired to provide an anode that can be easily and cheaply renewed or have 20 portions thereof renewed, if deterioration of the anode should be unequal.

A further object is to render that part of the anode subject to greatest electro-chemical 25 action more massive than those parts subject to less action.

Still another object is to provide a simple and convenient construction for an anode which will permit of the parts being made and easily assembled at the place of use and 30 the metallic parts joined together to form a unitary structure readily removable as a whole from the support therefor.

With these, and other, objects in view, the 35 invention may be embodied in the form described in this specification, reference being had to the accompanying drawing, in which

Figure 1 is a side elevation, partly broken away; Fig. 2 is a plan view of a portion of the apparatus; and Fig. 3 is an end elevation.

Reference numeral 1 designates a supporting rail of wood or other suitable material to which molten metal will not adhere on solidifying, having therein a plurality 45 of holes 2 the rail at the upper part of said holes being counterbored. A rod 3, preferably of lead, is inserted in each of holes 2, and has an enlarged portion 4, which rests on the rail of the bottom of the counterbore.

A short distance below rail 1 the rods are 50 reduced in diameter and about midway of their length and at their lower ends pass through stiffening strips 5 and 6 which have dowels 7 driven therethrough in such a manner as to contact with the sides of some of the rods and support the strips. A groove 8

is formed in the top of rail 1 and preferably terminates a short distance from each end of said rail. One of rods 3 is provided with a prolongation 9 at its upper end, in which a 60 wire 10 is cast and said wire may be connected to any suitable source of electric current. After the rods 3 are assembled in rail 1, melted lead is poured into groove 8, and upon solidifying, it forms a bar 12, connecting the rods 3, whereby current is distributed to all said rods from wire 10. The molten lead upon solidifying does not adhere to the supporting rail 1, so that the rods 3 may be readily removed from position 70 thereon, as a unit, when it is desired to make renewal or repairs.

This anode is used in a similar manner to those of the ordinary construction, as will be readily understood by those skilled in the 75 art to which this invention appertains.

Rods 3 being of larger diameter at the surface of the fluid, where the electro-chemical action is greatest, do not become eaten through at this point, as is usually the case, 80 rendering the anode useless.

I claim:

1. In an anode, a supporting rail, a groove therein, openings in said rail, a plurality of rods passing through said openings, enlarged portions on said rods adapted to rest on the portions of the rail surrounding the openings, and a metallic strip loosely fitting the grooves in said rail and joining said rods together to form a unitary structure removable from said rail.

2. In an anode, a supporting rail of wood, a groove therein, counterbored openings in said rail, a plurality of rods having heads fitting the counterbored portions of said openings, and a metallic strip cast in said grooves joining said rods together, forming a unitary structure removable from said rail.

3. In an anode for electrically precipitating metal from solution, a rail, a groove 100 therein, counterbored openings in said rail, a plurality of rods having heads fitting the counterbored portion of said openings and supported by said rail, an enlarged portion to each of said rods at the point of greatest 105 wear, and means in the groove of said rail to electrically connect together said rods and unite them in a unitary structure removable from said rail.

4. In an anode, a grooved supporting rail, 110 a plurality of rods supported in said rail by means of enlargements on the upper ends, a

metallic strip cast in the groove in said rail connecting said rods whereby they are removable as a unit from said rail, a prolongation of one of said rods, and a wire cast in 5 said prolongation.

5. In an anode for electrically precipitating metal from solution, in combination, a wooden rail provided with openings, metallic rods passing through said openings and supported by said rail, said rail provided with grooves extending between said rods, said grooves adapted to receive molten metal whereby said rods are connected together 10 electrically and mechanically forming a structure removable as a unit from said supporting rail.

6. An anode for electrically precipitating metal from solution, comprising a grooved supporting rail provided with openings 20 therethrough, tapered metallic rods passing through said openings and supported by said rail, metallic strips cast in the groove of said supporting rail, said strips connecting said

rods and forming a structure removable from said rail as a unit, and strengthening strips 25 associated with said rods.

7. In an anode for electrically precipitating metal from solution, in combination, a wooden rail provided with openings, metallic rods passing through said openings and supported by said rail, said rail provided with grooves extending between said rods, said grooves adapted to receive molten metal whereby said rods are connected together 30 electrically and mechanically, forming a unitary structure.

In testimony whereof, I have signed my name to this specification in the presence of two subscribing witnesses at Virginia City, Storey county Nevada this 23rd day of April 40 A. D. 1907.

ROBERT J. WISNOM.
